UNITED STATES PATENT OFFICE.

JOHN M. ROHLFING, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

RAILWAY-CAR END CONSTRUCTION.

1,109,599.

Specification of Letters Patent. Patented Sept. 1, 1914.

Application filed January 14, 1913. Serial No. 742,000.

To all whom it may concern:

Be it known that I, JOHN M. ROHLFING, a citizen of the United States, residing at St. Louis, Missouri, have invented a certain 5 new and useful Improvement in Railway-Car End Construction, of which the following is a full, clear, and exact description, such as will enable others skilled in the art to which it appertains to make and use the 10 same, reference being had to the accompanying drawings, forming part of this specification, in which—

Figure 1 is an elevational view of a car end of my improved construction. Fig. 2 15 is a vertical section taken on the line 2—2 of Fig. 1. Fig. 3 is a top plan view. Fig. 4 is a horizontal section taken on the line 4—4 of Fig. 1.

My invention relates generally to railway 20 car end construction, and more particularly to the construction of the car end wall.

In railway cars, and particularly those designed for and used in freight service, the 25 end portions of the car bodies, and particularly the end walls are subjected to great strains and stresses, not only because of the sudden starting and stopping of the cars and the consequent vibration, but by reason of the shifting of the load or contents of the 30 car while the latter is in transit, and also by reason of blows or shocks which said end wall may receive while the car is in service.

I propose to construct a car end from a plurality of sections of sheet metal, one or 35 more of said sections being corrugated so as to strengthen and stiffen the plate to a maximum degree, thus providing a construction which will effectively resist internally or externally applied stresses and blows, and 40 which will transmit such stresses and strains to the sill and plates of the car body frame.

The principal object of my invention is to construct the car end from a plurality of 45 pieces of material, preferably sheet metal, each piece or section being reinforced and stiffened by means of ribs or corrugations pressed in the metal, thus providing a comparatively simple, inexpensive construction which can be readily utilized with an ordinary 50 car underframe and superstructure, and which end will be effective in resisting stresses and strains resulting from shifting loads, ordinary service shocks and vibrations, or collisions.

55 A further object of my invention is to

construct a car end in sections, thereby making it possible to utilize comparatively small pieces of sheet metal in the formation of the completed end, which small pieces or sections can be more readily handled during 60 the formation of the stiffening ribs or corrugations than where a large single piece of material is utilized as the car end.

To the above purposes my invention consists in certain novel features of construction and arrangement of parts hereinafter more fully described and claimed.

As illustrated in the accompanying drawings, my improved car end is composed of a pair of side sections or panels 1 and 2 and a central section or panel 3. These sections or panels are preferably formed of approximately rectangular pieces of sheet metal, and formed in the side sections or panels 1 and 2 in any suitable manner are horizontally disposed stiffening ribs or corrugations 4.

The side and top edges of the sections 1 and 2 are bent rearwardly at right angles to the plane occupied by the main body portions of said sections in order to form marginal flanges 5, by means of which the end is attached to the car body frame. The lower edges of the sections 1 and 2 are bent outward into horizontal planes to form base 85 flanges 6 which rest directly upon the end sill or underframe of the car.

The main body portion of the central section or panel 3 occupies a plane in front of the plane occupied by the panels or sections 90 1 and 2, and said main body portion is slightly inclined so that its base occupies a position farther away from the panels or sections 1 and 2 than its upper end, and thus said central section performs the function 95 of a brace for the central portion of the end.

The side portions of the central section 3 are bent at right angles to the main body portion of said central section, as designated by 7, and these bent side portions fit directly against and are fixed to the outwardly bent inner edges 8 of the side sections 1 and 2. The rear edges of the bent portion 7 are flanged outward, as designated by 9, and fixed to the corresponding portions of the panels 1 and 2 by means of rivets or like fastening devices.

The upper end of the central section or panel 3 is bent rearwardly to form a flange 10 which corresponds with the flanges on the 110

upper ends of the sections 1 and 2, and the lower portion of said central section is bent outward to form a base flange 11, which, when the end is applied to the car, rests 5 directly upon the underframe or end sill.

In my improved construction of car end the ribs or corrugations 4 materially stiffen and reinforce the side portions of said end, and the central panel or section 3 stiffens 10 and reinforces the central portion of said end, and by virtue of such construction all internally and externally applied shocks or blows and all service strains and vibrations which tend to distort the end wall will be 15 effectively resisted.

By forming the end in three panels or sections of approximately equal size it is possible to utilize comparatively small sheets of metal, and this not only effects a considerable saving in the initial cost of construction, but enables the parts to be more readily handled by workmen during the formation of the ribs or corrugations and in the assembling of the ends than where 25 said end is formed of a single large piece of material.

It will be readily understood that minor changes in the size, form and construction of the various parts of my improved car end 30 can be made and substituted for those herein shown and described without departing from the spirit of my invention, the scope of which is set forth in the appended claims.

I claim:

35. 1. A car end comprising a plurality of panels or sections, the central one of which is offset to an increasing extent from top to bottom so that the major portion thereof occupies a plane in front of the vertical 40 plane occupied by the other panels, and said other panels having formed therein transverse stiffening ribs or corrugations.

2. A car end composed of a pair of side sections or panels, and a central section 45 forming a considerable portion of the end wall and disposed in a plane a substantial distance in front of the side sections and connected thereto by longitudinally directed flanges.

50. 3. A car end composed of three vertically disposed sections or panels, having their main portions disposed on lines parallel transversely of the car, the central one of which sections occupies a plane a substantial 55 distance in front of the plane occupied by the side sections.

4. A car end composed of sheet metal, the central portion of which occupies a plane a substantial distance in front of the plane 60 occupied by the side portions and forms a stiffening rib for the car end having its

major portion extending parallel to the side portions transversely of the car.

5. A car end composed of sheet metal, the central portion of which is offset with respect to the side portions to a gradually increasing extent from top to bottom and joined thereto by longitudinally directed flanges disposed substantially at right angles to said portions, and said side portions 65 being provided with horizontally arranged corrugations.

6. A car end composed of sheet metal, the central portion of which is offset with respect to the other portion and joined thereto 70 by flanges which increase gradually in width from top to bottom.

7. A car end constructed of sheet metal, the central portion of which occupies a plane in front of the plane occupied by the 80 side portions of the end, and said central portion being slightly inclined with respect to a vertical plane and connected to the side portions by webs disposed at substantially right angles thereto.

8. A car end composed of three vertically disposed panels, the outer ones of which are provided with stiffening corrugations, and the central one of which panels occupies a position in front of the plane occupied by 90 said outer panels; said central panel being connected to said outer panels by flanges extending at right angles to the faces of the panels and of gradually increasing width from top to bottom.

9. A car end constructed of sheet metal having a vertically extending middle portion offset with respect to the other portion and connected thereto by parallel flanges directed longitudinally of the car to 100 form a stiffening and bracing member, the lateral portions of the car end being provided with stiffening corrugations terminating adjacent the said offset bracing portion.

10. A car end constructed of sheet metal 105 having a vertically extending middle portion connected to the lateral portions by parallel webs extending longitudinally of the car and offset at the bottom of the end structure so as to form a stiffening and 110 bracing member for the lateral portions, and the lateral portions being provided with stiffening corrugations whereby the bracing influence of the offset portion may be transmitted throughout said lateral portions.

In testimony whereof I hereunto affix my signature in the presence of two witnesses, this eighth day of January, 1913.

JOHN M. ROHLFING.
